UNITED STATES PATENT OFFICE.

ROBERT JOHNSTON ROBINSON AND CYRUS F. COLLINS, OF LINNEUS,
MISSOURI.

CUTTER-BAR GUIDE.

SPECIFICATION forming part of Letters Patent No. 434,469, dated August 19, 1890.

Application filed April 2, 1890. Serial No. 346,348. (No model.)

To all whom it may concern:

Be it known that we, ROBERT JOHNSTON ROBINSON and CYRUS F. COLLINS, citizens of the United States, residing at Linneus, in the county of Linn and State of Missouri, have invented a new and useful Harvester Cutter-Bar Guide, of which the following is a specification.

This invention relates to harvesters, and 10 more particularly to the guide for the cutter-bars thereof.

The object of the invention is to provide a 15 guide for the purpose mentioned, which is adjustably connected to the guards and also to the finger-bar.

The invention consists of a movable bar forming the rear member of the guide and carrying friction-rollers, a slotted and shou- 20 dered strap passing around the finger-bar and engaging said movable bar, bolts through the latter engaging slots in certain of the guards and lateral arms on the latter forming the front member of the guide, as well as of adjunc- 25 tive and specific details and the construction and arrangement of the above parts, and certain auxiliaries tending to enhance the mechanical completeness of the whole, all as hereinafter more fully described, and as illus- 30 trated in the accompanying drawings, in which—

Figure 1 is a plan view of a section of this improved cutter-bar. Fig. 2 is a transverse section through one of the slotted straps. Fig. 3 is an enlarged perspective view of one of 35 the guards and its lateral arms.

Referring to the accompanying drawings, A designates the main finger-bar; B, the guards bolted to the bar A, as shown at C; D, a rearwardly-facing shoulder formed in the body 40 of the guards; E, the reciprocating cutter-bar; and F, the knives carried by the latter and passing through slots G in the guards, the cutter-bar E being guided between the shoulder D and the front face of a guide, all as is 45 common in devices of this character.

Coming now to the present invention, each guard B is provided with a shoulder 1, which rests against the front edge of the finger-bar A, and the body of the guard is provided with 50 lateral arms 2 at the points shown, having their extremities oppositely tongued and

grooved or concaved and convexed so as to engage each other. The rear face of each arm 2 forms the shoulder D above mentioned, and is grooved, as shown in the drawings. 55 The cutter-bar E reciprocates longitudinally just in rear of the grooved shoulder D, and the front edge of said cutter-bar is also grooved, as shown at 3. This cutter-bar is held, by means hereinafter described, above 60 the shank 4 of each guard, and its groove 3 therefore stands opposite the groove in the shoulder D.

When the cutter-bar is pressed forward, the edges thereof above and below its groove 65 abut closely against the edges above and below the groove in the shoulder D. By this means the cutter-bar has a double bearing on the front member of the guide throughout the entire length of the former. The guards 70 are also held properly spaced by their abutting lateral arms.

The numeral 5 designates a metallic bar resting upon the shanks 4 of the guards B in front of their shoulders 1, and journaled on 75 vertical pins 6 and seated in slots in this bar are friction-rollers 7, which bear against the rear edge of the cutter-bar E, and thereby constitute the rear member of the guide. Bolts 8 may be passed through the removable 80 bar 5, and their heads engage slots 10 in the guards B, whereby the movable bar 5 may be adjusted forward and back upon the shanks 4 to press the cutter-bar forward when necessary. We prefer, however, to hold the movable bar 5 in position by means of a metallic strap 20, which passes around the finger-bar A, and whose lower end is provided with a vertical shoulder 21 and horizontal lip 22, while its upper end is bent upwardly at 23 90 and provided with a horizontal lip 24, as shown in the drawings. The upper and lower arms of this strap are provided with one or more aligned slots 25, through which pass bolts 26, by means of which the strap may be 95 adjusted forward and back upon the bar A, and after it is adjusted the tightening of the bolts will clamp it against the upper and lower faces of the movable bar 5. In some cases we may use these straps, and also bolt 100 the bar 5 to the shanks 4, in order to give the parts greater rigidity.

The cutter-bar E reciprocates between the above-described shoulder D at its front side and friction-rollers 7 at its rear side, and also between the lips 22 beneath it and 24 above it, as will be readily understood. When it is desired to adjust the movable bar 5, the bolts 26 are loosened and the straps 20 moved as far as is necessary, after which the bolts are again tightened. If the bolts 8 are used, they are also loosened and tightened again after the adjusting has been accomplished. When it is desired to replace a guard-finger, the cutter-bar is first removed, and all that is necessary is to remove the bolt C, when the finger can be passed downwardly and disengaged from the supporting-bar in a manner which will be obvious.

The rollers 7 are preferably spaced from each other less than the length of reciprocation of the cutter-bar E, whereby the wear upon the latter will be even, as will be understood.

What we claim is—

1. In a harvester, the combination, with the finger-bar and the independent guard-fingers detachably connected thereto and having laterally-projecting arms engaging the arms on adjacent guards, the rear faces of said arms forming a shoulder, of a movable bar carrying friction-rollers and standing in rear of said shoulder, and means, substantially as described, for adjusting said movable bar forward and back, as and for the purpose set forth.

2. In a harvester, the combination, with the finger-bar, and guard-fingers carried thereby and having a grooved shoulder upon their shanks, and with a movable bar carrying friction-rollers, and means, substantially as described, for adjusting said movable bar forward and back, of the cutter-bar reciprocating between said shoulder and movable bar and having a groove in its front edge interlocking with that in the shoulder, as and for the purpose set forth.

3. In a harvester, the combination, with the finger-bar, and guard-fingers carried thereby and having a grooved shoulder upon their shanks, and with a movable bar carrying friction-rollers, an adjustable strap supporting 50 said movable bar, and integral lips thereon forward of the bar, of the cutter-bar reciprocating between said shoulder and movable bar and between said lips and having a groove in its front edge registering with that in the 55 shoulders, as and for the purpose set forth.

4. In a harvester, the combination, with the guard-fingers B, having the shoulders 1 on their shanks, the finger-bar A, bolted to said guards and against said shoulders, and the 60 reciprocating cutter-bar E, of the adjustable guide mounted upon the shanks of said guards forward of said shoulders, and means, substantially as described, for adjusting it forward and back thereon, as set forth. 65

5. In a harvester, the combination, with the finger-bar A, of the movable bar 5, the metallic straps 20, inclosing said bar A and supporting said movable bar at their front ends, the arms of these straps being provided with 70 aligned slots 25, and bolts 26, passing through said slots and through the body of the bar, substantially as described.

6. In a harvester, the combination, with the finger-bar A and the movable bar 5, of metallic straps 20, inclosing said finger-bar and provided with aligned slots through their bodies, bolts 26, passing through said slots, a shoulder at the front end of the lower member, and an upwardly-bent portion 23 in the body of 80 the upper member, between which said movable bar is clamped, as set forth.

In testimony that we claim the foregoing as our own we have hereto affixed our signatures in presence of two witnesses.

ROBERT JOHNSTON ROBINSON.
CYRUS F. COLLINS.
